UNITED STATES PATENT OFFICE.

CHARLES QUAST, OF MARION, OHIO.

GAS-ENGINE.

SPECIFICATION forming part of Letters Patent No. 597,326, dated January 11, 1898.

Application filed March 8, 1894. Serial No. 502,882. (No model.)

To all whom it may concern:

Be it known that I, CHARLES QUAST, a citizen of the United States, residing at Marion, in the county of Marion and State of Ohio, have invented certain new and useful Improvements in Gas-Engines, of which the following is a specification, reference being had therein to the accompanying drawings.

My engine is designed to operate under the Otto cycle, and it includes valve mechanism, igniter mechanism, a pumping mechanism, a governor, and a carbureter, the features of invention lying in the special arrangement and combination of parts, as will be herein-after pointed out.

In the accompanying drawings, Figure 1 is a side view of the engine, partly in section, through suction-valve and vaporizer. Fig. 2 is an end view of engine, partly in section, through both the inlet and exhaust valves. Fig. 3 is a sectional plan through valve-chamber, showing water and waste-heat jacket and also the igniter. Fig. 4 is a section through the pump mechanism. Fig. 5 shows water connection for valve-chest. Fig. 6 shows water-jacket of valve-chest.

Bed-plate 96 carries in bearings 111 crank-shaft 110, which carries on one end pulley 112 and on the other fly-wheel 116 and governor-pulley 117. Said bed-plate carries on posts 55 the cylinder, and this carries explosion-chest 4, which latter carries valve-chest 86. Crank-shaft 110 carries spur-gear 108, meshing with spur-gear 94, journaled in the post 55, and these gears are of a relation as one to two to each other in diameter. Gear 94 is keyed on shaft 118 in bearing 107 and carries on the end valve-cam 41 and igniter-cam 43. Valve-cam 41 engages with its periphery the roller 26 of lever 27, which is pivoted on bracket 49 of pedestal 55. Said lever 27 carries above roller 26 valve-rod 20, which is guided in bearing 24 and screws in governor-catch and combined valve-stem coupling 17, having lock-nut 19. Governor-catch carries in line with rod 20 valve-stem 15 and latter exhaust-valve 87. On the valve-stem 15 and between governor-catch and valve-chest 86 is spring 101. Igniter-cam 43 has a high point 12 to engage point 44 on igniter-lever 40. The lever 40 is connected by pivot 46 to igniter-rod 13, screwed in spring-bushing 12

with lock-nut 14. The spring-bushing carries spring 11 and at the top receives loose rod 9, with head 122, sliding in hole 10. Lever 40 is fulcrumed with strap 39 on eccentric 38. Eccentric 38 has a tail or lever 35, with a thumb-screw 36 to slide on a segment 37 to secure early or late explosion. The lever 27 carries, by a fulcrum 28, the lever 29, having a slot to 60 receive a bolt 32, connected to a pump-rod 33 and to the lever by a thumb-screw 93, as in Fig. 4. The lever 29 carries on one end a latch-lever 51 in hinge 52 with a handpiece 53. The latch-piece 51 carries a pin 50, which 65 fits into a socket 51^x in the fulcrum-pin 92. The lever 29 has a handle 54, which carries a spring 91, pressing against the handpiece 53 of the latch 51. The pump-rod 33 is connected with the pump-piston 57 by the pivot 70 56, which fits in pump-cylinder 58, the latter being provided with suction and discharge valves. In the suction-pipe 61 is the shut-off valve 59. The pipe 60 admits the oil or gas to the mixing or vaporizing chamber 71. The 75 governor-frame 103 carries a spindle 22, balls 104, and pulley 105. The spindle 22 connects on one side by 81 with the valve-dog 18 and by the finger 23 with igniter-rod 3, the latter being guided in 23 by the eye 119. The rod 80 3 carries the collar 7, and between this and the guide 5 the spring 6 is located. The rod 3 is pivoted to the lever 2, which is fulcrumed at 1 and has an extension 76 with point 98. The fulcrum 1 reaches through stuffing-box 85 83 into chamber 77, and there carries the said extension 76 to contact with the electrode 85, to which the circuit-wire 84 is connected.

The engine works on the four-cycle system—that is, it makes one explosion every two revolutions or every four strokes. As the crank-shaft makes one revolution the valve, pump, and igniter mechanism make a half-revolution and make an entire revolution during each two revolutions of the crank-shaft or to 95 each four strokes of the piston. As cam 41 rotates with gear 94 the high part 47 will raise the roller 26, lever 27, pump-lever 29, pump-rod 33, pump-piston 57, also valve-rod 20, governor-catch 17, valve-stem 15, and exhaust-valve 87. This rising occurs every other revolution of the engine if not up to 100 speed, these actions allowing the waste products of combustion to escape and pumping a

new charge of explosive material into the vaporizer and mixer as the roller 26 leaves the high part 47 of cam 41. After the exhaust has taken place the suction takes place and 5 sucks in the explosive mixture pumped into the vaporizer, while the exhaust-valve closes. The exhaust takes place when the piston moves toward the combustion-chamber and the exhaust-valve is open, and the suction 10 takes place as soon as the piston commences to leave the combustion-chamber, and at the same time the suction will raise the suction-valve 75. After the piston has reached the 15 point farthest from the combustion-chamber and returns, the suction-valve will fall and the compression begins, as the gases cannot escape. As soon as the piston has reached the nearest point to the combustion-chamber again cam 43 has turned and brought point 20 42 in contact with 44 of igniter-lever 40 and raised same, also rod 13, rod 3, compressed spring 6, and brought spark-lever 76 in contact with electric rod 85. As lever 40 rises and points 8 and 9 of igniter-rods touch, then 25 rod 3 will follow the motion of rod 13, and as soon as spark-lever 76 touches electric rod 85 the rod 3 will stop moving upward, and as 13 still proceeds the spring 11 in bushing 12 will compress the rod 9, move in hole 122, 30 and head 10 will slide in bushing to allow the bushing to continue the motion given by rod 13 and lever 40. By the time piston 99 has reached the nearest point of the combustion-chamber then the points 42 and 44 have 35 reached the highest point and point 44 will drop upon cam 43, leaving point 42 and so releasing the compressed springs 11 and 6. Spring 6 forces the rod 3 to its proper position, this bringing the spark-lever 76 out of 40 contact with electric rod 85, and the separation causes a spark sufficient to ignite the compressed gases. The moment of the separation of spark-lever 76 from electric rod 85 is regulated by moving lever 35 of eccentric 45 38 on segment 37, this releasing the high points 42 and 44 sooner or later, which causes an earlier or later explosion. These explosions will continue until the engine has reached the speed to which the governor is 50 set. As soon as that speed is reached dog 18 will be shoved by governor-spindle 22 toward the valve-rod 20, and dog 18, engaging governor-catch 17, will prevent the exhaust-valve 87 from closing, this preventing the 55 suction of new gases. At the same time igniter-rod 3 will be brought out of line with rod 9 through the governor moving 23 and guide 119. This prevents rod 9 from striking rod 8, and also the sparkler will not operate or go through its motions. Also lever 27 is held in a high position through governor-catch 17, and cam 41 will only raise it a little, just enough to allow the governor to withdraw the dog 18, this preventing the engine 60 from sucking gases in improper time, as the suction only takes place right after the exhaust-valve closes. The governor-dog is ful-

crummed right near valve-rod 20, taking all strain away from the governor, so as not to interfere with the sensitiveness of same. As long as lever 27 is held by catch 17 and dog 18 the pump holds a charge of explosive, and as soon as lever 27 drops then the charge is discharged into vaporizer 71. The amount of charge is regulated by moving fulcrum 3 in slot 31 to increase the stroke of the pump-piston 57. This shows that the entire mechanisms are in rest as soon as the engine is up to speed and can only commence operation again at the proper time. In starting the engine a few strokes of lever 29, carried by valve-lever 40, will send a charge of explosive into vaporizer 71. In handling lever 29 the hand of the operator will take hold of hand-piece 54 and pressing 53 toward 54, thus drawing pin 50 out of hole in fulcrum 92 and making lever 29 free, pivoted on fulcrum 28. Then a few strokes can be made. By releasing the handpieces 54 and 53 the pin 50 will be forced back again in fulcrum 92 and locks the lever 29 with lever 27 and couples same to make the motions as the latter does, this transmitting all motions of lever 27 through rod 33 upon pump-piston 57. The explosive pumped into chamber 71 runs over overflow 95 65 upon spreader 66, having holes, and allow the explosive, if a liquid, to run through and over same upon lower screens 64. As the engine sucks the air passes through openings 123 of hull 69 and passes along outside the walls of chamber 70 and through the bottom of vaporizer 71 into screens 64 and 63, mixing with the explosive and passing through mixing-chamber 71, between screens 63 horizontally and screens 63 vertically, through valve-seat 75 into chamber 77, where it is ignited at the proper time. After exploding and expanding the exhaust takes place. The waste products are expelled through chamber 70, passing past the walls of chamber 77 and the entire vaporizer 71, this heating the explosive as it is charged into the vaporizer and also the entire passage of same. As the exhaust passes on it reaches the larger part of chamber 70, right below the muffler 72, this 115 allowing the gases to expand, giving off heat to the walls 86 and condensing. In passing through muffler 72 still more condensation takes place, and the expansion at the same time brings the waste products at an atmospheric pressure and temperature, this making a quiet exhaust. As the air enters openings 123, passes along the walls of muffler 72, absorbing heat from the same, and by passing along walls of 86 the air gets quite hot, this air passing through the bottom opening of the vaporizer and uniting with the heated explosive, vaporizes the same quickly and perfectly. Passing on through the screens and chambers 71 and 121, the mixed gases are still 125 heated, and by the time they reach the exploding-chamber they are very hot and make an easy and high explosion. Hull 69 prevents the weather, wind, rain, and snow from af-

fecting the mixing and vaporizing of the explosive. Gate 67 facilitates the examination of the interior part of the hull and bottom of vaporizer. In this manner the waste products of combustion heat first the explosive, then the air, and also the mixture after being mixed.

Water-jacket 88, Figs. 3 and 5, around exhaust-valve chamber prevents said chamber from getting overheated and igniting the gases before the spark takes place.

The bottom of the hull 69 also will be used in cold weather to light the first charge of gases or liquid to heat the vaporizer for starting up.

It will be noticed from Fig. 1 that the igniter mechanism has two predetermined positions—one for later and the other for an earlier explosion—and that the adjustment by means of the cam, the lever, and segment is positive and accurate, it being only necessary to shift the lever from one position to the other in order to adjust the point of explosion accurately. This adjustment is entirely independent of the adjustment in taking up the wear, which is done by the parts 12, 13, and 14.

I claim as my invention—

1. In combination, the cylinder, the piston, the crank-shaft, the valve-cam, the valve, the rod 20 extending upwardly from the cam to the valve, the lever positively connected with the rod and engaging the cam, the spring for pressing the rod down, the pivoted governor-catch, the catch, in the valve-rod, and the governor rotating about a horizontal axis and the reciprocating rod 22 extending horizontally and connected directly to the governor-catch, substantially as described.

2. In combination, in a gas-engine, the cylinder and piston, the valve mechanism with operating means therefor, the igniter, the igniter-rod 3, the rod 9 arranged to strike the same, the means for operating the rod 9 from the engine crank-shaft, and the governor connected with the rod 3 for shifting the same out of line with the rod 9, said governor being independent of the rod 9 and having driving connection with the crank-shaft substantially as described.

3. In combination in a gas-engine, the cylinder and piston, the valve mechanism, with means for operating the same, the igniter, the rod connections thereto, the lever 45, the eccentric 38 on which the lever is pivoted, the igniter-cam, said lever having a tailpiece 35 and the segment in which said tailpiece is adjusted to vary the position of the lever, substantially as described.

4. In combination, the cylinder and piston, the exhaust-valve, the rod leading thereto, the catch for controlling the return of said rod and the seating of the exhaust-valve, the igniter, the rod 3 for operating the same, and the governor comprising the reciprocating shaft 22, having an arm connected with the catch and a second arm connected with the

igniter-rod to control both of the said parts, substantially as described.

5. In combination, the cylinder and piston, the valve mechanism including the lever 27, the pump and the connection thereto from the lever 27 including the lever 31 pivoted thereto at 28 at one end and having a hand-releasing catch engaging with the lever 27 at or near its other end, substantially as described.

6. In combination, in a gas-engine, the cylinder and piston, the valve mechanism, the conduit 71 leading to the inlet-valve, the fuel-supply pipe leading to said conduit, the outer casing 69 and inclosing the conduit 71 communicating with the outside air and the conduit 71, the exhaust-valve, the exhaust-passage therefrom extending along the inlet-casing 71, the exhaust-chamber 70 within the outer air-inlet casing 69 inclosing the conduit 71 and the muffler communicating with the chamber 70 and also extending through the outer casing 69, substantially as described.

7. In combination, the cylinder, the piston, the valve mechanism including the inlet and exhaust valves, the chamber 121 in which the inlet-valve is located and the conduit 70 leading from the exhaust about the chamber 121 and the inlet-valve 75, substantially as described.

8. In combination, the cylinder, the piston, the valve mechanism including the inlet and outlet valves, the inlet-valve chamber 121, the vaporizer-chamber 71 and the conduit leading from the exhaust-valve about the inlet-valve chamber and the vaporizer-chamber, substantially as described.

9. In combination, the cylinder and piston, the valve mechanism including the inlet and exhaust valves, the exhaust-chamber 86, the muffler 72 connected therewith, and the hull 69 inclosing both the exhaust-chamber and the muffler and having the inlets for the air whereby the air is led along the heated walls of the muffler 72 and the exhaust-chamber 86, substantially as described.

10. In combination, the cylinder and piston, the valve mechanism, the vaporizer-chamber arranged to be heated by the exhaust, the fuel-supply pipe 60 leading into the vaporizer-chamber, the overflow 65, and spreader 66 therein and the inlet for the air at a point below the overflow and spreader whereby the oil will be heated before mixing with the air, substantially as described.

11. In combination, the cylinder and piston, the valve mechanism, the vaporizer-chamber 71, the chamber 77 in which the ignition takes place and the intermediate chamber 121 all of said chambers being heated and acting to raise the temperature of the mixture before ignition, substantially as described.

12. In combination in a gas-engine, the cylinder, the inlet-valve, the vaporizer, the air-inlet chamber connecting directly with the vaporizer-chamber, the mixing-chamber beyond the vaporizer-chamber and between the

same and the inlet-valve and the exhaust-conduit extending by the mixing-chamber and arranged to heat also the vaporizer-chamber and the air-inlet chamber whereby the air and oil will be heated separately and after vaporization the air and vapor will be heated while mixing, substantially as described.

13. In combination in a gas-engine the cylinder, the inlet-valve, the vaporizer-chamber, the air-inlet chamber comprising a shell inclosing the vaporizer-chamber, the mixing-chamber between the vaporizer and the inlet-valve and the exhaust-conduit extending around the mixing and vaporizer chambers and through the air-inlet chamber whereby the oil and air will be heated separately and after vaporization the vapor and air will be

mixed and heated before passing through the inlet-valve, substantially as described.

14. In combination, the piston and cylinder, the valve mechanism, an igniter and igniter-cam, a lever connected with the igniter and pivotally supported, the pivot of said lever being an eccentric, a lever connected with the eccentric and means for limiting the throw of said lever to two predetermined positions, substantially as described.

In testimony whereof I affix my signature in presence of two witnesses.
